UNITED STATES PATENT OFFICE.

CHARLES M. DEMING, OF DAYTON, OHIO.

INDICATOR.

1,377,006.

Specification of Letters Patent.

Patented May 3, 1921.

Application filed June 22, 1916, Serial No. 105,177.

Renewed September 29, 1920. Serial No. 413,636.

To all whom it may concern:

Be it known that I, CHARLES M. DEMING, a citizen of the United States, residing at Dayton, in the county of Montgomery and 5 State of Ohio, have invented certain new and useful Improvements in Indicators, of which the following is a specification.

This invention relates to indicators, the object of the invention being to provide an 10 article of this character which is susceptible of ready manipulation and by which deviations in work being gaged can be quickly and precisely shown.

In the drawings accompanying and forming part of the present specification I have 15 shown in detail certain convenient forms of embodiment of the invention which I will set forth fully in the following description. I do not restrict myself to this disclosure; 20 I may depart therefrom in several respects within the scope of the invention defined by the claims following said description.

Referring to said drawings:

Figure 1 is a top plan view of an indicator 25 involving the invention.

Fig. 2 is a side elevation of said indicator.

Fig. 3 is a longitudinal section of the same showing in elevation part of an attaching shank.

Fig. 4 is a top plan view of a lathe showing the indicator in co-operative relation therewith.

Fig. 5 is a top plan view of the feeler 35 member and needle, and gage member, the latter being in dotted lines, and the feeler member and needle being shown by dotted lines as moved in one direction from the normal neutral point.

Fig. 6 is a top plan view partly in section of the body and gage members, the front portion of the body member being broken away, the feeler member being omitted and the needle shown by dotted lines 45 to an adjusted neutral position.

Fig. 7 is a detail view in top plan partly in section of the rear portion of the body member, of part of the needle and certain coacting elements.

Figs. 8 and 9 are details of nose pieces.

Figs. 10 and 11 are detail views of the forward portion of a modified form of feeler with different kinds of nose pieces connected therewith.

Like characters refer to like parts through-

out the several views which are on different scales.

As may be inferred one of my primary purposes is the provision of an article having means for indicating errors in a piece 60 of work. The indicator has as a part of it a feeler member which is preferably moved laterally which is obviously more advantageous than one which moves endwise or longitudinally. The nose or tip end of this 65 feeler member can be applied to the work in any convenient manner, depending upon the nature of the work. The work, as will be obvious, may be any shape, that is to say it may be flat or round or a combination 70 of the two, or it may be of such kind as may require internal gaging or on the other hand external gaging. The invention, however, does not concern the character of work to be gaged, for the indicator can be employed in any connection in which those 75 of the ordinary type are used. Hereinafter I will describe one of the large number of modes of utilizing the implement.

The device includes in its construction a 80 body portion such as that denoted in a general way by 2. The manner in which the body portion is mounted depends upon the use to which the article is to be put. In Fig. 4 the indicator is shown mounted 85 upon a lathe, and I will first briefly describe the principal parts of this machine and then a way in which the indicator of which the body 2 forms a part can be connected thereto. Said lathe has a bed 3, 90 the head-stock of which is equipped with a spindle 4, said bed having ways to receive the slide 5 equipped with the tool post 6 adapted to receive the shank 7. This shank is shown furnished at its inner end with a 95 projection 8 rising therefrom, threaded at its upper end to fit the threaded socket 9 in the underside of the body 2 substantially centrally of the length thereof. As will be clear this is merely one of several 100 simple ways of mounting the body 2. As shown the attaching shank 7 is oblique to the line of movement of the slide 5 so as to maintain the body 2 practically in parallelism with the line of motion of the slide 105 to adapt the feeler member hereinafter described to engage the circumferential surface of the work 10 chucked to or otherwise suitably connected with the inner end of the spindle 4. In this particular showing 110

the work 10 rotates with the spindle and with the feeler member hereinafter described in contact with its periphery. Where the interior of work is to be gaged, 5 the nose or tip of the feeler member would be introduced into the work. In some cases the work will remain at rest while the feeler member will be revolved or moved relatively to it. These are, however, details of use 10 and need not be discussed at length, for as I have already observed, it is only necessary to show one method of using the device.

Said device includes a feeler member such 15 as that denoted in a general way by 11. As already noted this feeler member is laterally movable, and the best effects I obtain by pivotally mounting it and preferably in such manner as to secure a long arm and a short 20 arm, the short arm being adapted to directly engage the work to be gaged, while the long arm has a suitable operative connection with a needle, pointer or equivalent element. By reason of this pivotal mounting of the feeler 25 member and the variations in length of its two arms, that part of the feeler member which engages the work has but a very small movement which is multiplied in the needle, owing to the fact that the needle is connected 30 with the long arm or branch of the feeler member. The feeler member shown in Figs. 1 to 3 for instance, involves a main section 35 as 12 and an auxiliary section or nose piece as 13, the shank of the nose piece being removably fitted in a socket in the front end of the main section 12, so that a nose piece of different kind can be substituted for that illustrated. As shown the terminal or work engaging part of the nose piece is spherical 40 as denoted by 14, although this is merely one of several different kinds of tips. The main section 12 of the feeler member is pivotally mounted. The body 2 at the forward end and on the upper side thereof has a bridge- 45 piece 15 from which the projection 16 extends forward, this projection 16 being complementary to the projection 17, the two projections presenting a fork to receive the enlarged part 18 of the feeler member 11, 50 this enlarged part receiving the coaxial pivot screws 19. The two screws jointly constitute a convenient pivotal mount for the feeler member or lever 11. The main section 12 of the feeler member extends under the 55 bridge-piece or arch 15, being flattened practically its entire length back of the arch. The under flattened surface of the feeler member is contiguous to the corresponding upper surface of the body 2. Said body 2 just back of the sides of the arch or bridge-piece 15 has the upward extensions 20 in transverse alignment, these extensions being a little higher than the thickness of the flattened part of the main section 12. Said 60 extensions 20 constitute a convenient support 65

for a gage member as 21 under which the feeler member or flattened part thereof extends freely, the extensions 20 spacing the gage member 21 from the feeler member. As may be inferred the gage member may 70 be of any character suitable for the purpose. That shown is arcuate, having a properly graduated scale on its upper or exposed surface. It may be mounted in any desirable manner. It abuts against the back of 75 the arch 15 and may be welded to said arch and also to the upper faces of the two side extensions 20. It will be clear on reference to Figs. 1, 2 and 3, that the forward arm 80 of the feeler lever 11 is considerably shorter than the rear arm, and this together with the manner in which the long arm is connected with the needle hereinafter described, gives to said needle a considerably greater angular movement than the short or forward arm 85 of the feeler lever.

Coöperative with the gage member 21 is a needle as 22. This needle or pointer tapers from its butt toward its free end, the latter being adapted to traverse the 90 scaled part of the gage member 21. The mount of this needle or pointer will be hereinafter described. It has a normal neutral position as shown in Fig. 1 at which point its free end is exactly over the center 95 graduation of the scale, the needle being movable oppositely from this neutral position in accordance with the direction of movement of the feeler member 11. In addition to this normal neutral position there 100 are two shifted or adjusted neutral positions as shown in Fig. 6, and these are obtained by a relative adjustment of the gage member and the needle, the best effects being obtained by the adjustment of the needle, 105 although this may not be required in all cases, for obviously the function in question might be otherwise secured. The body 2 at its rear end is shown provided with a loop 110 23, the lower part of the loop extending slightly below the body while the upper part of the loop is arched over by the body. Tapped through the top and bottom of the loop are coaxial cone-pointed screws 24 which fit conical seats in the butt part 25 of the 115 needle from which, as will be evident, the latter has a swinging movement.

The effect of the feeler member 11 is transferred to the needle in any desirable way. As illustrated the rear part of the 120 feeler has a slot 26 open at its outer end to receive the depending pin 27 of the needle, this pin being as shown comparatively close to the center of oscillation of the needle and naturally at a point removed from the 125 axis of swing of the feeler member, by reason of which the increase in motion of the tip of the needle with respect to the tip of the feeler member is obtained.

The feeler member and the needle are 130

normally maintained in neutral position whether it be the normal neutral position of the needle or the shifted or adjusted position thereof in some desirable way, and 5 spring means, one advantageous form of which will be hereinafter set forth, answer satisfactorily in this connection. In the rear upper surface of the body is shown a cavity or chamber 28 across the upper open side 10 of which the feeler and needle swing. This chamber or cavity presents a convenient means for receiving the needle-controlling spring means. While two springs as 29 and 30 are shown and are advantageous, it 15 will be clear that one spring or spring means of a different type might be substituted. The two springs are in parallelism and are spaced apart a distance to receive between them the pendent pin 27 of the needle, the two springs jointly acting to hold 20 the needle in its normal neutral position as shown for instance by full lines in Fig. 5. The springs are bent toward each other, their shanks fitting face to face and snugly 25 in a notch 31 in the upper side of the body 2 leading forwardly from the rear wall of the cavity 28. The two springs are shown occupying their normal position by full lines in Fig. 6. They are under tension, 30 and their effects are applied equally to the pin 27 to thus yieldingly hold said needle in the normal neutral position.

It will be supposed that the spherical tip 14 of the feeler 11 is applied to the work 10 and that the latter is turning owing to the 35 rotation of the spindle 4. Should there be an error of projection on the work, this will cause the feeler 11 to swing outward in the direction of the arrow in Fig. 5, thus 40 through the described parts swinging the needle 22 to the dotted line position in Fig. 5 or to some intermediate point in such direction, the amount of movement of the needle depending of course, upon the inaccuracy 45 of the work. When the inaccuracy is passed, the spring 30 acting against the pin 27 returns the needle to its normal neutral position. Should the inaccuracy be below the parts are oppositely moved, the 50 needle in this case moving from its neutral position shown in Fig. 5, owing to the corresponding upward movement of the tip of the feeler 11.

The springs 29 and 30 can be so operated 55 as to effect the movement of the needle 22 to either of its adjusted neutral positions from the normal neutral position, one of the adjusted positions being shown by dotted lines in Fig. 6. When the needle is in the 60 other adjusted position, its tip will be over the other outer graduation of the gage member 21. To effect the action of the springs any convenient means may be provided, although that shown will now be set forth. In the depression 32 at the rear end 65 of the chamber 28 is the disk 33 having an eccentric or crank pin 34 situated between the free portions of the two springs 29 and 30. This disk is provided with a downwardly extending central pin 35 extending 70 through the boss 36 depending from the rear end of the body 2. The lower projecting end of the pin has driven onto it the thumb piece 37 which may be peripherally milled and which is held to the pin by the 75 screw 38. By rotating the thumb piece 32 the pin 35 and disk 33 will be turned, so that the pin 34 can be revolved to change the positions of the two springs 29 and 30 from their normal. When the pin or crank 34 is 80 in normal position as shown by full lines in Fig. 6 for illustration, it is intersected practically by the longitudinal axis of the body 2. By turning the thumb piece or head 37 to carry the pin 34 upward in Fig. 6, the 85 free portion of the tensioned spring 30 will be correspondingly moved, the spring 29 following the companion spring and acting against the pin 27 serving to move the needle 22 to its adjusted neutral position. 90 When the needle is in the adjusted neutral position, it moves in, indicating along the scale of the gage member 21, and is returned to neutral solely by the action of the spring 30. By operating the thumb piece 95 37 to swing the pin 34 downward to effect corresponding movement of the needle, the action of the springs will be exactly reversed, and in this event only the spring 29 will act to return the needle 22 to its adjusted neutral position when shifted through the intervention of the work.

In Figs. 8 and 9 I show a different form of nose piece denoted by 39 and circular, the shank of this nose piece being insertible in the socket at the front end of the main section 12 of the feeler. This is merely one of a large variety of different types of nose pieces.

In Figs. 10 and 11 the main section 12' of the feeler has connected with it the pivoted part 40 perforated as at 41 to receive the shank of the nose piece 42. The axis of movement of the pivoted member 40 is at right angles to that of the feeler member 12'. 110 The nose piece 43 may be substituted for the nose piece 42 and its shank may extend through the perforation 41 and also into the socket 44 of the feeler section 12' so as to lock the pivoted part 40 against movement and thus make the nose piece 43 in effect a rigid extension of the feeler section 12'.

Obviously the device is extremely sensitive, and as a consequence proportionately 125 precise. While both the feeler and the needle of whatever form they may take, may be pivotally mounted in any desirable manner, the cone-pointed screws are highly satisfactory, providing not only for the deli- 130

cate mounting of the parts but at the same time providing also for wear which is compensated for by setting up the screws. The needle, as will be clear, constitutes a convenient indicating member. It is conceivable, therefore, that in some cases the gage member 21 might be dispensed with.

What I claim is:

1. A device of the class described comprising a body, a feeler member, the body being provided with pivots to mount the feeler member to present long and short branches, a needle pivotally mounted at its butt, upon the body, the needle having an operative connection with the long branch of the feeler, a pair of springs of equal force supported by the body, the free ends of the springs acting against the needle, and means acting on the free ends of the springs to adjust the same in a plane parallel to that of the swing of the needle.

2. A device of the class described comprising a body, a feeler member pivotally supported between its ends upon the body and having long and short branches at opposite sides of its pivotal mount, a needle pivotally mounted at its butt end upon the body, the needle having an operative connection with the long branch of the feeler, a pair of springs of equal force mounted upon the body, the feeler having a pin to enter between the springs and the springs acting against the pin at opposite sides thereof and a pivotally adjustable disk in the body, the disk having an eccentric pin to fit the space between the free portions of the springs whereby the relative pressures of the springs on the first-named pin may be adjusted.

3. A device of the class described comprising a body portion, a feeler, means on the body portion, for supporting the feeler for swinging movement between its ends to present long and short branches, a needle, and means on the body portion for supporting the needle for swinging movement, the long branch of the feeler having a slot and the needle having a pin extending into the slot, the pin being adjacent the axis of motion of the needle, a pair of springs mounted on the body portion of approximately equal effect and acting against opposite sides of the pin, and a manually operable rotary disk on the body portion having an eccentric pin disposed in the space between the free portions of the springs.

4. A device of the class described comprising a body, a feeler member, the body being provided with coaxial cone-pointed screws and the feeler member having seats to receive the cone ends of the screws, the seats being located to present long and short branches on the feeler, a needle having sockets at its butt, the body having cone-pointed screws, the cones of which fit the sockets in the butt, the needle having a pin and the long branch of the feeler having an open-ended slot to receive the pin, a pair of springs of equal force, the body having a chamber in which the springs are mounted and the springs acting against opposite sides of the pin, and a rotary disk in the chamber, having an eccentric pin to fit the space between the free portions of the springs.

5. A device of the class described comprising a body, a feeler member, the body being provided with coaxial cone pointed screws and the feeler member having seats to receive the cone ends of the screws, the seats being located to present long and short branches of the feeler, a needle having sockets at its butt, the body having cone pointed screws, the cones of which fit the sockets in the butt, the needle having an operative connection with the long branch of the feeler, a pair of springs of equal force supported by the body, the free ends of the springs acting against the needle and means to adjust the springs laterally.

6. A device of the class described comprising a body, a feeler member, the body being provided with coaxial cone pointed screws and the feeler member having seats to receive the cone ends of the screws, the seats being located to present long and short branches of the feeler, a needle having sockets at its butt, the body having cone pointed screws, the cones of which fit the sockets in the butt, the needle having an operative connection with the long branch of the feeler, a pair of springs of equal force supported by the body, the free ends of the springs acting against the needle, and means to enter between the free portions of the springs to adjust the same laterally.

In testimony whereof I affix my signature in presence of two witnesses.

CHARLES M. DEMING.
